Patented Mar. 24, 1925.

Des. 66,863

UNITED STATES PATENT OFFICE.

CLIFTON N. KEITH, OF SPRINGFIELD, OHIO.

DESIGN FOR A BADGE OR THE LIKE.

Application filed August 3, 1923. Serial No. 6,930. Term of patent 3½ years.

To all whom it may concern:

Be it known that I, CLIFTON N. KEITH, a citizen of the United States, residing at Springfield, in the county of Clark and State of Ohio, have invented a new, original, and ornamental Design for a Badge or the like, of which the following is a specification, reference being had to the accompanying drawing, forming part thereof.

The figure of the drawing is an extended plan view showing my new design.

I claim:

The ornamental design for a badge or the like as shown.

In testimony whereof, I have hereunto set my hand this 25th day of July, A. D. 1923.

CLIFTON N. KEITH.

Witnesses:

DAVID A. KERSTING,
GEORGE C. HELWIG.
